UNITED STATES PATENT OFFICE.

EDWIN REYNOLDS, OF PROVIDENCE, RHODE ISLAND.

RUBBER STAMP.

SPECIFICATION forming part of Letters Patent No. 396,233, dated January 15, 1889.

Application filed August 29, 1887. Serial No. 248,217. (No model.)

To all whom it may concern:

Be it known that I, EDWIN REYNOLDS, a citizen of the United States, residing at Providence, in the State of Rhode Island, 5 have invented a new and useful Improvement in Rubber Stamps, of which the following is a specification.

My invention relates to that class of rubber stamps which include the combination 10 of the rubber die with the inking-pad; and it consists in the combination of the die-holder and the pad-holder, a shank, to which the said die-holder and pad-holder are pivoted, and a case sliding upon the shank and 15 adapted to cause the opening or closing of the die and pad holders and to hold the same securely in their closed position, as herein-after fully set forth.

Figure 1 is a longitudinal section illustrating my improvement, showing the rubber die 20 in position for use, the sliding case being in its backward position. Fig. 2 is a similar section, showing the sliding case in position for holding the die and pad in contact with 25 each other in a folded position. Fig. 3 represents a transverse section taken in the line $x x$ of Fig. 2.

In the accompanying drawings, A represents a pencil, which is provided with a removable point-cap, B. Upon the upper end 30 of the body a of the pencil is placed the hollow shank C, to the upper end of which is pivoted the die-holder D, the side b of the hollow shank C being left open for the purpose of receiving the die-holder D and the pad-holder E when in their folded position, 35 as shown in Fig. 2. To the side of the shank C, at a distance from its end, is pivoted the pad-holder E. The die-holder D is held in a transverse position for use, as shown in Fig. 40 1, by means of the spring c , which is coiled around the pivot d , and the pad-holder E is also held in an outwardly-extended position by means of the spring e , which is coiled 45 around the pivot f . The back g of the die-holder D strikes against the edge i of the rear side, h , of the shank, thus serving to limit the backward movement of the die-holder under the action of the spring c , and 50 the backward movement of the pad-holder E

is limited by the edge j of the end of the holder, which strikes against the inner side of the back h of the shank.

Upon the cylindrical portion k of the hollow shank C is placed the sliding case F, 55 which is enlarged at its upper end, and is also cut away at the side l , in order to make allowance for the required pivotal movement of the pad-holder E. The enlarged upper portion, F' , of the sliding case F is provided 60 longitudinally with a fixed partition, m , thus forming a segmental chamber, n , within which is placed the pen-slide o , which is operated by means of the screw-stud p , passing through the slot q in the sliding case. 65 Upon moving the sliding case F forward from the position shown in Fig. 1 the edge r of the partition m will first strike against the back g of the die-holder, and thus cause the die-holder to turn upon its pivot d to meet 70 the pad-holder E, which is also caused to turn upon its pivot f toward the die-holder by means of the shoulder s of the sliding case, which strikes against the cylindrically-formed back portion t of the pad-holder E, 75 and when the sliding case F has been carried to its extreme forward limit the rubber die G and the ink-pad H will be brought into close connection with each other, as shown in Fig. 2. The pad-holder E is preferably made 80 with a cylindrically-shaped back, t , and in this case is provided with a fixed partition, u , which serves to form a supporting-back for the inking-pad H.

Upon moving the sliding case F back to 85 contact with the annular stop w at the lower end of the shank C, the die G will be automatically turned to its position for use, as shown in Fig. 1.

By means of my improved sliding case the 90 die and pad will be securely held for carrying in the pocket, and the required opening and closing movement of the die and pad can be made with great rapidity and convenience.

I claim as my invention—

1. In combination, the spring-operated die-holder pivoted to the shank, the spring-operated ink-pad holder, also pivoted to the shank, and the case adapted by its sliding movement 100

upon the shank to cause the opening or closing of the die and pad, substantially as described.

2. In combination, the spring-operated die-holder pivoted to the shank, the spring-operated ink-pad holder, also pivoted to the shank, and the slotted case provided with a pen-slide

and adapted to cause the opening or closing of the die and pad, substantially as described.

EDWIN REYNOLDS.
